UNITED STATES PATENT OFFICE.

ELLA H. DALE, OF ROCHESTER, NEW YORK.

DESIGN FOR A TRUCK.

53,843.

Specification for Design.

Patented Sept. 16, 1919.

Application filed April 21, 1919. Serial No. 291,749. Term of patent 14 years.

To all whom it may concern:

Be it known that I, ELLA H. DALE, a citizen of the United States, residing at Rochester, in the county of Monroe and State of New York, have invented a new, original, and ornamental Design for a Truck, of which the following is a specification, reference being had to the accompanying drawing, forming part thereof.

Fig. 2 is a side view; and
Fig. 3 is a bottom view.

I claim:
The ornamental design for a truck as shown.

ELLA H. DALE.
